United States Patent Office

Des. 223,136

Patented Mar. 21, 1972

223,136

BRUSH

John Jedora, 33 Cedar St. N.,
Timmins, Ontario, Canada

Continuation-in-part of design application Ser. No. 20,141,
Nov. 17, 1969. This application Dec. 21, 1970, Ser.
No. 26,733

Term of patent 14 years

Int. Cl. D4—02

U.S. Cl. D4—15

FIG. 1 is a front view of a first form of brush according to my design;

FIG. 2 is a side view of the brush of FIG. 1;

FIG. 3 is a back view of the brush of FIG. 1;

FIG. 4 is an underside view, as seen from beneath FIG. 3;

FIG. 5 is a front view of a second form of brush according to my design;

FIG. 6 is a side view of the brush of FIG. 5;

FIG. 7 is a back view of the brush of FIG. 5; and

FIG. 8 is an underside view, as seen from beneath FIG. 5.

This is a continuation-in-part of design application Ser. No. D. 20,141, filed Nov. 17, 1969, and now abandoned.

I claim:

The ornamental design for a brush, as shown and described.
